The ornamental design for a perfume bottle, as shown and described.

DESCRIPTION

FIG. 1 is a front view of a perfume bottle showing the new design.

FIG. 2 is a right side view thereof, and the left side view and rear side view are mirror images thereof.

FIG. 3 is a top view thereof.

FIG. 4 is a bottom view thereof; and,

FIG. 5 is a front, top and left side perspective view thereof. The speckled surface shading applied to the transparent cap portion of the perfume bottle in FIGS. 1, 2, 3 & 5 illustrate a contrasting appearance with respect to the lower transparent bottle portion of the claimed design.

The broken lines in FIGS. 1-5 depict portions interior of the cap that form no part of the claimed design.
